DESIGN FOR A JAR

Ernest A. Hinkins, Washington, Pa., assignor to Tygart Valley Glass Company, Washington,
Pa., a corporation of West Virginia

Application January 19, 1940, Serial No. 89,582

Term of patent 7 years

To all whom it may concern:

Be it known that I, Ernest A. Hinkins, a citizen of the United States, residing at Washington, in the county of Washington, State of Pennsylvania, have invented a new, original, and ornamental Design for a Jar, of which the following is a specification, reference being had to the accompanying drawing, forming a part thereof.

Fig. 1 is a side view of a jar embodying my new design; Fig. 2 is a side elevational view thereof, partly in section, and Fig. 3 is a bottom plan view of the jar.

I claim:

The ornamental design for a jar, as shown.

ERNEST A. HINKINS.
